UNITED STATES PATENT OFFICE.

THOMAS KENNARD THOMSON, OF YONKERS, NEW YORK.

LIGHTHOUSE CONSTRUCTION.

No. 838,821.

Specification of Letters Patent.

Patented Dec. 18, 1906.

Application filed August 23, 1905. Serial No. 275,360.

To all whom it may concern:

Be it known that I, THOMAS KENNARD THOMSON, a citizen of the United States, and a resident of Lowerre, Yonkers, in the county of Westchester and State of New York, have invented certain new and useful Improvements in Lighthouse Construction, of which the following is a specification, reference being had to the accompanying drawings, forming a part thereof.

This invention relates particularly to the construction of lighthouse-foundations which are built above water and then sunk into position.

It has for its object the provision of such a structure as will afford a strong and stable support for a lighthouse under the severest conditions to which it may naturally be subjected, and, furthermore, to provide such a structure as shall be capable of being readily sunk into position whereby the placing of the same may be accomplished with great expedition.

Heretofore lighthouse-foundations built above water and sunk into position have, as a general rule, either been very unstable when in position, owing to the buoyancy of the base thereof, or have required an unusually large amount of labor and time in their placing. These difficulties the present invention is designed to overcome.

In the drawings, in which the invention is illustrated, Figure 1 is a view in central vertical section of one embodiment of the improved structure, and Fig. 2 is a view showing the base in plan and the pillar in horizontal section.

In Fig. 1 of the drawings the structure is represented as already sunk into position with its base resting in the bed or bottom of a body of water the level of which is indicated at *a*, the bed or bottom of the body of water being shown as made up of different strata, such as mud *b* and sand *c*.

The structure, which may be built on shore or on the surface of the water, as desired, comprises a pillar secured to or integral with a base which spreads out around the pillar, so as to form a firm and stable bottom for the pillar to rest upon.

The pillar may be composed of concrete or the like or of reinforced concrete or may be a steel pillar or, in fact, may be formed of any suitable material or materials. In the present case it is shown as formed of concrete *d*, with iron or other metallic side plates sur-

rounding the same, which side plates serve to strengthen the concrete body and to protect it from the action of the water. The pillar, for convenience in construction, may be built with a hollow space *f*, which may subsequently be filled up with sand, concrete, or any other suitable substance, if desired.

The base of the structure, which spreads out around the lower end of the pillar, so that it is relatively broad as compared with the pillar, is preferably formed with a frame *g* of wooden beams, in which there is provided an air-chamber *h* for the workmen while the structure is being placed in its permanent position, the said chamber communicating with the hollow space *f*, or with any space which extends above the surface of the water, by means of shafts, such as the shaft *i*. Upon this frame *g* is placed a sufficient quantity of concrete or other suitable material *k*, the weight of which, together with the weight of the pillar and the other parts of the structure, is amply sufficient to offset the buoyancy of the wooden portions of the frame.

In order to sink the structure with expedition, a coffer-dam *l* may be built upon the base, and for this purpose the frame *g* is preferably extended upward at the sides of the base to the desired extent. The concrete *k* may then be placed into the bottom of the coffer-dam and upon the top of the working chamber, and enough concrete may be thus laid to nearly overcome the buoyancy of the structure as a whole. Then by introducing water into the coffer-dam the structure can be gradually sunk into position. The coffer-dam of course may be made as large and extensive as desired, the proportions shown in the drawings being illustrative only and not binding, and when the structure is in its final position the coffer-dam may be removed or filled with stones, sand, concrete, or any other material, as the conditions of each particular case may dictate.

Such a structure as the present one obviously furnishes an absolutely stable support for a lighthouse. The pillar, although subjected to the action of a strong current and beating waves, will not, on account of its relative narrowness, receive force enough or sufficiently heavy shocks to disturb the structure as a whole, nor will the base be buoyant and tend to upset the structure, as in many of the constructions heretofore employed.

Various changes may be made in the pres-

ent structure without departing from the spirit of the invention, and accordingly the improvements are not limited to the single embodiment of the invention herein specifically referred to.

I claim as my invention—

1. In a structure to be built above water and sunk into position to serve as the foundation of a lighthouse, the combination of a pillar adapted to support a superstructure, a base therefor, and a coffer-dam built upon the base, as and for the purpose set forth.
2. In a structure to be built above water and sunk into position to serve as the foundation of a lighthouse, the combination of a pillar adapted to support a superstructure, a base therefor which spreads out around the

pillar, and a coffer-dam built upon the base, substantially as and for the purpose set forth.

3. In a structure to be built above water and sunk into position to serve as the foundation of a lighthouse, the combination of a pillar adapted to support a superstructure, a base therefor consisting of a frame forming a working chamber below and a coffer-dam above, and a filling of concrete in the bottom of the coffer-dam, as and for the purpose set forth.

This specification signed and witnessed this 7th day of August, A. D. 1905.

T. KENNARD THOMSON.
